J. L. Parker,

Water Wheel.

No 8,429.

Patented Oct. 14, 1851.

UNITED STATES PATENT OFFICE.

JAMES L. PARKER, OF SHIRLEY VILLAGE, MASSACHUSETTS.

IMPROVEMENT IN WATER-WHEELS.

Specification forming part of Letters Patent No. 8,429, dated October 14, 1851.

To all whom it may concern:

Be it known that I, JAMES L. PARKER, of Shirley Village, in the county of Middlesex and State of Massachusetts, have invented a new and useful Improvement in the Turbine or Horizontal Water-Wheel; and I do hereby declare that the same is fully described and represented in the following specification and accompanying drawings, letters, figures, and references thereof.

In the said drawings, Figure 1 denotes a horizontal section of my improved wheel or turbine and its flume and directing-passages. Fig. 2 is a vertical and transverse section of the same.

A in the said drawings represents the wheel; B, the ring of directing-passages; C, the flume; D, the vertical axle, and E the supporting-frame of the wheel. The ring of directing-passages is composed of a series of curved passages *a a a*, arranged in a circle and leading out of a common central flume C, whose bottom is represented at *b* and as having the axle of the wheel passed through it. The wheel is composed of a horizontal circular disk *c*, in which is arranged vertically and in a circle a series of buckets *f f f*, &c., as seen in Fig. 2, these buckets being covered by a circular ring *e e*, which is disposed on them and parallel to the disk *c*.

Between each two buckets and between the front face of the back part of one of them and the rear face of such side of the others of them and about midway between the same I arrange a vertical and curved partition *d*, so as to make, as it were, two passages *g* and *h*, leading into each bucket, each of the said

partitions being made to extend inward beyond the said two buckets (or the circle in which their inner edges are situated) a distance toward the ring of discharging-mouths, as seen at *i*.

The direction in which the wheel revolves is denoted by the arrow *O*.

The water in rushing out of any one of the discharging-passages *a a*, &c., will first flow into the passage *h* of a bucket, as denoted by the arrow *k*. It strikes into the buckets, as denoted by the arrows *l m*, and drives the air which may be in the bucket out through the passage *g* and around the inner end of the bucket, as denoted by the arrow *n*, or through an air passage *p* and into the bucket in rear, where it can freely flow away. The water acting on a wheel constructed in such a manner meets with very little obstruction from air in the buckets, and is enabled in consequence thereof to operate without any material loss of power, which would otherwise be likely to be produced by the retention of air in its buckets.

What I claim as my improvement is—

The combination of the curved partition *d* and the air space or passage *p* with each two buckets and for the purpose of causing the escape of air from the bucket into the next one in rear, all substantially as specified.

In testimony whereof I have hereto set my signature this 11th day of August, A. D. 1851.

JAMES L. PARKER.
